UNITED STATES PATENT OFFICE.

HUGH BURGESS, OF ROYER'S FORD, PENNSYLVANIA.

CENTRIFUGAL EXTRACTOR FOR SUGAR-CANE JUICE AND OTHER LIQUIDS.

SPECIFICATION forming part of Letters Patent No. 239,222, dated March 22, 1881.

Application filed January 24 1881. (No model.)

To all whom it may concern:

Be it known that I, HUGH BURGESS, a subject of the Queen of Great Britain and Ireland, residing in Royer's Ford, Montgomery county, Pennsylvania, have invented certain Improvements in Centrifugal Extractors for Sugar-Cane Juice and other Liquids, of which the following is a specification.

The object of my invention is to construct a machine for rapidly and thoroughly extracting juices from sugar-cane or liquids from other substances by the combined action of centrifugal force and direct pressure.

In the accompanying drawings, Figure 1, Sheet 1, is a vertical section of my improved centrifugal extractor; Fig. 2, Sheet 2, a plan view; Fig. 3, a sectional plan on the line 1 2, Fig. 1, and Fig. 4 a sectional plan on the line 3 4.

20 A is a vertical shaft, having its upper bearing in a box secured to a suitable frame, of which the beam B forms a part, and its lower bearing in a step, b, secured to a suitable foundation, d. This shaft is tubular, and its upper end has a stuffing-box for admitting the end of a pipe, D, which is furnished with a suitable stop-valve.

The screen consists, in the present instance, of substantial ribs f, preferably of T-iron, 30 these ribs being properly bound together and arranged at such a distance apart that there shall be narrow openings between them. The upper end of the screen, comprising the ribs f, is properly secured to a ring, h, against which bear horizontal disks or rollers i, the spindles of which have their bearings in plates F secured to the frame-work of the machine, the rollers (of which there may be three or more) serving to maintain the upper end of 40 the screen as it revolves concentric with the shaft A. The lower end of the screen rests in and is properly secured to the ring j of a casting, G, the ring being connected to the hub K of the casting by a number of lugs, m, 45 for a purpose explained hereinafter. This screen-supporting casting is adapted to and can turn independently of the shaft A, and is driven by a wheel which gears into the wheel L, the latter being secured to the hub of the 50 said casting. Another wheel, M, is secured to the shaft A below the wheel L, and be-

tween the two wheels there is a loose collar, n, on the shaft A. The screen is contained within a casing, N, which has three outlets, two of which, p p', are for the discharge of the 55 extracted liquids or juices, the third outlet, P, being for the escape of the waste cane or bagasse or other material from which the liquid has been extracted.

It will be seen that the screen is gradually 60 contracted in diameter from the top to a flange, x, below which the screen is enlarged at y, and is again gradually contracted from this point to the ring j of the casting G. The object of this peculiar shape of the screen will be 65 rendered apparent hereinafter.

The flange x, previously referred to, projects from and rotates with the screen, and it overlaps a flange, q, projecting from the interior of the casing N, so that all the liquids discharged 70 from the screen above the flange x must escape from the outlet p. In like manner the flange j, secured to the lower end of the screen, overlaps a flange, q', projecting from the interior of the casing, so that all the liquids which are 75 discharged from that portion of the screen between the two flanges x and j must pass through the outlet p'.

That portion of the shaft A which is contained within the screen has a spiral flange, w, 80 which varies in diameter as the screen varies, so that there may be as little space as possible between the edges of the flange and the screen. It is not essential to my invention, however, that this spiral flange should be continuous, 85 for a system of oblique blades somewhat like those of a propeller may be secured to the shaft.

The operation of the above-described machine is as follows: In treating sugar-cane, for instance, for the extraction of the saccharine juices, the cane, cut into comparatively small lengths, is fed into the top of the screen, and under the influence of the spiral flange w of the revolving shaft A the cane is fed downward 90 until the whole space within the screen is tightly packed with the cane. As the cane descends it must necessarily be subjected to a continuously-increasing pressure, due to the gradual contraction of the upper portion of the screen. The 95 cane, under this pressure, yields its saccharine juices, which, by centrifugal force due to the 100

rapidly-rotating screen, are discharged through the spaces between the ribs forming the screen, the juices striking against the interior of the casing and passing from the latter through the outlet p into any suitable receptacle. But as all the juices may not be extracted from the cane when it has reached the point x , water is discharged from the orifices t in the tubular shaft at this point, where the screen is enlarged, so that the cane, after passing through the contracted upper portion of the screen, is saturated with water, and the enlargement of the screen permits the mass of cane to expand and absorb this water, after which it is again subjected to gradually-increasing pressure and the water is extracted, carrying with it the juices which it has washed from the cane, the combined water and juices being expelled by centrifugal force and passing through the outlet p' . The waste disintegrated cane or bagasse passes from the lower end of the screen between the lugs which connect the ring j and hub K of the casting G , and thence through the outlet P .

As regards the speed of the screen and the shaft A , it may be remarked that the speed of the former must be determined by the centrifugal force to dispose of the juices extracted by the pressure due to the spiral flange of the rotating shaft; but there must always be such a difference between the speeds of the screen and that of the shaft that while the former discharges the juices by centrifugal action the latter exerts a downward pressure to extract the juices from the cane. The shaft A must be rotated in a direction determined by the direction in which the flange is coiled round the shaft, or according to the direction in which the oblique blades are inclined, so that downward pressure may be exerted on the material to be operated upon.

An important result is attained by the arrangement of gearing described. When the machine is in operation the strain is exerted upwardly on the shaft and downwardly on the screen, so that the down-pressure on the top of the collar n between the two wheels will be counteracted by the upward pressure of the shaft against the under side of the said collar, and the step b will be relieved from that downward pressure of the shaft, which is a serious objection in many cases where vertical shafts are used.

In operating on some materials the expansion of the screen at y and the admission of water at this point may be unnecessary, the screen being made on a gradual taper through-

out; but in operating on sugar-cane I prefer this expansion of the screen.

I have referred above to the cutting of cane into comparatively short lengths before it is fed to the machine, but there may be a plate, s , on the beam B of the frame, as shown in Figs. 1 and 2, and the stalks of cane can be held perpendicularly over the mouth of the screen, and a knife, s' , on the upper edge of the flange w may strike the stalks against the said plate, and thereby sever the same into suitable lengths. The use of the peculiar screen shown and described, while preferred, is not absolutely necessary, as screens of perforated plate or like material may be employed.

I claim as my invention—

1. The mode herein described of extracting juices from sugar-cane or liquids from other substances, the said mode consisting in applying pressure to the cane or other material in a rapidly-revolving screen, substantially as set forth. 80

2. The combination of the tapering screen and shaft A , having a spiral flange or inclined blades, with gearing, whereby the within-described differential rotation is imparted to the said screen and shaft. 85

3. The combination of the shaft A , having a spiral flange or oblique blades, the screen and the flange x , with the outer casing, N , having an internal flange, q , and outlet p , as specified. 90

4. A centrifugal machine in which a tapering screen and a shaft having a spiral flange or oblique blades are combined with an outer casing, N , having an outlet or outlets for the liquid extracted and a separate outlet for the material from which the liquid has been extracted, substantially as set forth. 95

5. A centrifugal machine in which a tapering screen enlarged at a point between its upper and lower end is combined with a tubular shaft having a spiral flange or inclined blades and orifices through which water or other liquid can be discharged at or near the point of enlargement of the screen, as specified. 100

6. The within-described screen, consisting of T-bars bound together, with spaces between, as set forth.

In testimony whereof I have signed my name to this specification in the presence of two subscribing witnesses.
